UNITED STATES PATENT OFFICE.

PAUL CRICCHIO, OF NEW YORK, N. Y., ASSIGNOR TO MAJESTIC LAMP WORKS, OF NEW YORK, N. Y., A PARTNERSHIP CONSISTING OF PHILIP SILBERHARTZ, JACOB SILBERHARTZ, AND HARRY SCHEINER, ALL OF BROOKLYN, NEW YORK.

DESIGN FOR A FRAME FOR CLOCKS OR ARTICLES OF ANALOGOUS NATURE.

Application filed April 24, 1929. Serial No. 30,998. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Frame for Clocks or Articles of Analogous Nature, of which the following is a specification, reference being had to the drawing, forming a part thereof.

In the drawing:

Figure 1 is a front elevational view of the frame for clocks or articles of analogous nature; and

Figure 2 is a diagrammatic side outline view of the same.

I claim:

The ornamental design for a frame for clocks or articles of analogous nature substantially as shown.

PAUL CRICCHIO.
